Patented Nov. 23, 1915.

INVENTOR.

John P. Pride
By his Attorney,
R. L. Woodward

UNITED STATES PATENT OFFICE.

JOHN PENNELL PRIDE, OF LEICESTER, ENGLAND, ASSIGNOR TO UNITED SHOE MACHINERY COMPANY, OF PATERSON, NEW JERSEY, A CORPORATION OF NEW JERSEY.

FASTENING-INSERTING MACHINE.

1,161,074.

Specification of Letters Patent.

Patented Nov. 23, 1915.

Application filed March 18, 1915. Serial No. 15,379.

To all whom it may concern:

Be it known that I, JOHN P. PRIDE, a citizen of the United States, residing at Leicester, Leicestershire, England, have invented certain Improvements in Fastening-Inserting Machines, of which the following description, in connection with the accompanying drawings, is a specification, like reference characters on the drawings indicating like parts in the several figures.

This invention relates to fastening inserting machines for use in the manufacture of boots and shoes and particularly to the foot plates or work abutments of such machines.

Fastening inserting machines in which the shoe supported during the fastening inserting operation by a work support or horn, are provided with foot plates against which the shoe is clamped by the horn during the driving of the fastening. It is often found necessary to tip the shoe on the horn in order to properly present certain portions of the shoe to the fastening mechanism, particularly when the shoe has a narrow toe. When the shoe is so tipped on the support difficulty is often experienced in clamping the work to the best advantage and also without damaging the work between the foot plate and the horn during the fastening inserting operation.

An object of the present invention is to provide for machines of the class described an improved foot plate having provisions for accommodating itself to the different angular positions in which the shoe is positioned on the horn when it is clamped against the foot plate by the horn, thus affording a substantially wide bearing surface against which the shoe may be securely clamped by the horn and also preventing the shoe from being displaced on the horn or damaged through the work clamping pressure.

Other objects and features of the invention will be more fully explained in the following description and then pointed out in the claims.

In the drawings: Figure 1 is a side elevation of a portion of a fastening inserting machine embodying the present invention; Fig. 2 is a plan view of the foot plate; Fig. 3 is a section on the line 2-2 of Fig. 2, and also showing the relative position of the foot plate and the shoe.

The invention is preferably shown as embodied in a pegging machine of the type shown and described in United States Letters Patent No. 581,066 granted to Davey *et al.*

The machine, briefly, comprises a head 2 containing the pegging mechanism and supported by a column 3 and a vertically reciprocating horn 5 which supports the shoe and is actuated to clamp the shoe against the foot plate or work abutment 6 which is secured to the under side of the machine head, during the driving of the peg.

The foot plate 6, as shown, consists of a shank portion 8 by which it is secured rigidly to the under side of the machine frame and a laterally broadened forward portion 9 which is provided with an elongated slot 12 extending in the direction of the feed of the work and through which the awl and driver may pass in their respective operations on the shoe.

In accordance with this invention the under side of work engaging face of the portion 9, about the slot 12, is provided with a concaved recess 13, curved in a direction transverse to that of the slot and extending the length of said slot, and a work engaged plate 16 is loosely retained in this recess by the overhanging lips 17, Fig. 2, at either end of the recess. The plate 16 is also provided with an elongated slot 18 registering with the slot in the head and of sufficient width to allow the awl and driver to project through regardless of the different positions the plate may assume in the recess.

The plate is limited in its transverse movement in the recess by a stud 19 threaded into the plate 9 and having a portion of its head engaging shoulders provided on the rear edge of the plate. The work engaging face of the plate is preferably roughened to prevent it from slipping on the work.

It will be noted with this construction of presser foot that when the shoe is tipped on the horn, (as shown in Fig. 3) in order to position the portion of the work which is to receive the peg directly beneath the driver, and the shoe then raised by the horn to be clamped against the presser foot during the driving of the peg, the foot plate 16 adjusts itself in the recess 13 in accordance with

the plane in which the tread surface of the sole is presented, thereby providing a substantial bearing surface against which the work may be firmly clamped by the horn 5 during the peg inserting operation. Furthermore, the clamping pressure of the horn is equally distributed over a larger portion 10 of the work which prevents the work from being distorted or damaged and insecurely clamped between the foot plate and the end 15 of the horn as was heretofore the case when only a portion of the foot plate engaged the work and supported it against the comparatively strong clamping pressure of the work support.

Having described a preferred embodiment of my invention, I claim as new and desire to secure by Letters Patent of the United States:—

20 1. A foot plate for a fastening inserting machine consisting of a laterally broadened portion having a slot extending in the direction of the work feed and provided with a recess curved in a direction transverse to that of the slot and extending the entire length of said slot, and a work engaging plate movably retained in said recess and adapted to be moved by engagement of the work into parallelism therewith in the different angular positions in which the work 25 is presented.

2. In a fastening inserting machine, a foot plate including a laterally broadened portion having a slot extending in the direction of the work feed and having in its 30 lower face a recess curved in a direction transverse to the direction of the slot, and extending the length of said slot, a work engaging plate fitted into said recess and movable therein into the different angular 35 positions in which the work is presented to it, and means for retaining the plate in said recess.

3. In a fastening inserting machine, a

foot plate including a laterally broadened 45 portion having a slot extending in the direction of the work feed and having in its lower face a recess curved in a direction transverse to that of the slot and extending the length thereof, a work engaging plate 50 movably retained in said recess and adapted to accommodate itself in said recess to the different angular positions in which the work is presented thereto, and means arranged to retain the plate in said recess. 55

4. A foot plate for a fastening inserting machine, including a laterally broadened portion having a slot extending in the direction of the feed of the work and provided with a concaved recess curved in a direction transverse to that of the slot, and extending the entire length thereof, a work engaging plate fitted into said recess and having a slot registering with the said first 60 mentioned slot, and means for retaining said plate in said recess.

5. A foot plate for a fastening inserting machine, including a laterally broadened portion having a slot extending in the direction of the feed of the work, and provided with a concaved recess in the under side thereof curved in a direction transverse to that of the slot, and extending the entire length thereof, a work engaging plate fitted into said recess and having a slot registering with said first mentioned slot, and means arranged to retain said plate in said recess, 70 said last mentioned slot being of sufficient width to allow the fastening inserting instrumentalities to pass therethrough in any 75 of its adjusted positions in the recess.

In testimony whereof I have signed my name to this specification in the presence of two subscribing witnesses.

JOHN PENNELL PRIDE.
